(57) **CLAIM**

The ornamental design for locking pliers, as shown and described.

DESCRIPTION

FIG. 1 is a perspective view of locking pliers showing my new design;

FIG. 2 is a right view thereof;

FIG. 3 is a left view thereof;

FIG. 4 is a front view thereof;

FIG. 5 is a rear view thereof;

FIG. 6 is a top view thereof; and,

FIG. 7 is a bottom view thereof.

The broken line shown in the drawing disclosure represents the environment of the claimed design and forms no part thereof.
